UNITED STATES PATENT OFFICE.

BENJAMIN H. THOMPSON, OF SCHENECTADY, NEW YORK, ASSIGNOR TO GENERAL ELECTRIC COMPANY, A CORPORATION OF NEW YORK.

PROTECTIVE DEVICE.

1,375,981.

Specification of Letters Patent. Patented Apr. 26, 1921.

Application filed August 28, 1919. Serial No. 320,524.

To all whom it may concern:

Be it known that I, BENJAMIN H. THOMPSON, a citizen of the United States, residing at Schenectady, in the county of Schenectady, State of New York, have invented certain new and useful Improvements in Protective Devices, of which the following is a specification.

My invention relates to protective devices and especially to relays and has for its object to provide an overload relay of the retarded type which operates with a constant and definite minimum time delay upon overloads in excess of a predetermined amount.

Overload relays of the retarded type operate in a time which is a measure of the overload up to a predetermined amount but upon excessive overloads, due to conditions of short circuits, such relays frequently operate, practically instantaneously, regardless of their time setting. This feature is undesirable, particularly upon systems of distribution in which a number of these relays are connected to operate in predetermined time intervals or in a predetermined sequence.

In the relay embodying the features of my invention, I overcome these difficulties in the operating of time limit relays, by providing means whereby such relays operate in a time which is a measure of the overload up to a predetermined amount and upon overloads above the predetermined amount, with a definite minimum time which is constant, independent of the excessive or overload current. This function is obtained by modifying the operating characteristics of the relay by means of a device so connected in the relay circuit that a resultant potential is impressed upon the relay which varies as the excess current up to a predetermined value or amount and then remains constant independent of the current.

The novel features which I believe to be characteristic of my invention will be definitely indicated in the claims appended hereto, while the features of construction and mode of operation will be understood from the following description taken in connection with the accompanying drawings, in which:

Figure 1 is a diagrammatic illustration of a time limit overload relay, of the induction type, embodying the principles of my invention, and Figs. 2 and 3 show graphically the

characteristics of a relay embodying the features of my invention.

In Fig. 1 I have shown my invention embodied in an electroresponsive device or overload relay 1 which, by way of illustration, is shown as of the induction type comprising an actuating or motive means which consists of two coöperating electromagnetic elements 2 and 3 and a retarding element; such as a drag magnet 4 operating on a rotatably mounted induction disk 5 to control the relay contacts, not shown. The electromagnetic elements 2 and 3 comprise suitable actuating windings 6 and 7 respectively, with their operating magnetic circuits. These actuating windings 6 and 7 are connected in the circuits of secondary windings 8 and 9, respectively, of a transformer 10 having a primary winding 11 operatively related to the current transformer 12 connected to the conductor 13, the circuit of which is controlled by the relay 1. The auxiliary transformer 10 is, therefore, connected between the main transformer 12 and the relay 1 and has a magnetic circuit 14 arranged to magnetically saturate upon currents above a predetermined amount in conductor 13 and hence in primary winding 11. As both actuating windings 6 and 7 are energized from the auxiliary transformer 10, the circuit of one winding, for instance winding 6, is made more highly inductive, in order to produce a sufficient phase displacement between the fluxes set up by windings 6 and 7, to create a rotative effect on the disk 5. Due solely to the saturation effect of the auxiliary transformer 10, the potential impressed across the secondary windings 8 and 9 and hence the current which will flow through the actuating windings 6 and 7 of the relay, increases as the first power of the current in conductor 13 up to a predetermined amount which corresponds to the saturation of transformer 10 and on further increases of current, the potential impressed across the windings 8 and 9 is not constant but increases gradually as the primary current increases. This relation can best be shown in Fig. 3 in which the curve A shows the variation in voltage impressed across the secondary winding 8, for instance, with the variations of current in the primary winding 11, relying merely on the effect of saturation of the transformer 10. It is observed that the voltage across winding 8

continues to increase gradually even after transformer 10 saturates, due to the fact that it is practically impossible to obtain complete magnetic saturation. The effect of 5 the saturation of transformer 10 alone is also shown in Fig. 2 by the curve B which gives the time current characteristics of the relay. This curve, upon currents above a value necessary to cause saturation, has a 10 gradually sloping, long, tail portion b. In relays of this type, the minimum time setting for the relay is not constant and upon extremely heavy overloads such relays will operate practically instantaneously.

15 According to my invention, I provide means for so modifying the operating characteristic that the relay operates with a constant and definite minimum time of operation on overloads or current values above a 20 predetermined amount or an amount necessary to saturate transformer 10. Instead of utilizing the potential which is impressed on the secondary winding 8 to furnish the energizing current for the actuating winding 6, I utilize a resultant potential which 25 varies as the primary current up to a predetermined amount and then remains constant independent of further increases in primary currents. For obtaining this resultant potential, I provide a current limiting means, such as a resistance element 15, which is in the circuit of primary winding 11 of auxiliary transformer 10 and across 30 which a potential drop occurs which varies 35 directly as the current in the primary winding 11. The relation of the potential across element 15, for variations in primary current, is best shown by curve C of Fig. 3. The circuit of the secondary winding 8 is 40 then so related to the circuit including resistance element 15 that the potential impressed on the secondary winding 8 and the potential across the resistance element 15, oppose or buck each other to give a resultant potential for energizing the actuating winding 6 as best shown by curve D of Fig. 3 which is a resultant of curves A and C. It will be observed that the resultant voltage impressed across relay winding 6 rises 45 with the current until a current occurs sufficient to magnetically saturate transformer 10 when the resultant potential becomes constant independent of the current in primary winding 11. The modifying effect of the current limiting means or resistance 50 15 upon the time current characteristics of the relay is best shown in Fig. 2 by the curve E. This curve, it will be observed, has a substantially horizontal or flat tail 55 portion instead of the gradually sloping tail portion of curve B which gives the relay a constant and definite minimum time of operation upon overloads in excess of a predetermined amount.

60 65 As is well known, the number of turns in

circuit of the primary winding 11 of the auxiliary transformer 10 is adjustable, the primary winding 11 having taps to vary the pick-up current for the relay, that is the current required to start the relay into operation, and in order to proportionally vary the opposing or bucking potential, the resistance element 15 is also adjustable or has a similar number of taps as the primary winding 11. 75

In accordance with the provisions of the patent statutes, I have described the principle of operation of my invention, together with the apparatus which I now consider to represent the best embodiment thereof; 80 but I desire to have it understood that the apparatus shown is only illustrative and that the invention can be carried out by other means.

What I claim as new and desire to secure 85 by Letters Patent of the United States, is:—

1. In combination a transformer having a magnetic circuit adapted to saturate on currents above a predetermined amount, a primary and a secondary circuit, for said transformer, means in said primary circuit so related to said secondary circuit to produce a resultant voltage which is a measure of the primary current up to a predetermined amount and is then constant independent of 90 the amount of current, an overload relay, and an actuating winding for said relay energized in response to said resultant voltage.

2. In combination a transformer having 100 a magnetic circuit adapted to saturate on currents above a predetermined amount, a current limiting means in the primary circuit of said transformer having a voltage drop proportional to the current in said circuit, a secondary circuit so related to said current limiting means that the voltage impressed across said means opposes the voltage impressed across the secondary winding of said transformer, and an electroresponsive 110 device having an actuating winding energized in response to said resultant voltage.

3. A relay comprising an actuating winding responsive to overload current, means for impressing on said winding a potential which 115 varies as the overload current up to a predetermined amount and which is constant upon overloads above said predetermined amount, including a transformer having a secondary circuit supplying said actuating winding, and means for opposing the potential induced in said secondary circuit by a potential which varies as the current in said primary winding.

4. A relay comprising operating means 125 responsive to overload current, a transformer controlling said operating means, and means associated with said transformer for impressing a potential on said operating means which varies as the overload 130

current up to a predetermined amount and is then constant independent of the overload current.

5. In an overload relay, an operating member, electroresponsive means for controlling the movement of said operating member, and means for modifying the characteristics of said electroresponsive means to move said operating member in a time inversely proportional to the overload up to a predetermined amount and in a constant minimum time on overloads above said predetermined amount.
6. In an overload relay, an operating member, electro-responsive means for controlling the movement of said operating member, and means for modifying the characteristics of said electro-responsive means comprising a transformer having a magnetic circuit adapted to saturate on predetermined overloads, a resistance in the pri-

mary circuit of said transformer, and a secondary circuit for controlling said operating means so related to said resistance to receive a potential which is a resultant of 25 the potential drop across said resistance and the potential induced in said current.

7. In an overload relay, an operating member, electro-magnetic means controlling said member, a transformer having a primary circuit, a secondary circuit therefor controlling said electromagnetic means and adapted to receive a current proportional to said primary current up to currents of a predetermined amount, and means associated with said primary and secondary circuits to maintain the current in said secondary circuit constant on primary currents above said predetermined amount.

In witness whereof I have hereunto set 40
my hand this 27th day of August, 1919.

BENJAMIN H. THOMPSON.
